US0D1105004S

(12) **United States Design Patent** (10) **Patent No.:** **US D1,105,004 S**
(45) **Date of Patent:** **** Dec. 9, 2025**

(54) **CABLE GUIDE**

(71) Applicant: **3M INNOVATIVE PROPERTIES COMPANY**, St. Paul, MN (US)

(72) Inventors: **David M. Blomberg**, Lino Lakes, MN (US); **Patrick R. McKellips**, Stillwater, MN (US)

(73) Assignee: **3M Innovative Properties Company**, St. Paul, MN (US)

(**) Term: **15 Years**

(21) Appl. No.: **30/021,207**

(22) Filed: **Sep. 3, 2025**

Related U.S. Application Data

(60) Division of application No. 29/979,944, filed on Dec. 20, 2024, now Pat. No. Des. 1,095,456, which is a division of application No. 29/945,664, filed on Jun. 4, 2024, now Pat. No. Des. 1,055,002, which is a continuation of application No. 29/790,031, filed on Nov. 1, 2021, now Pat. No. Des. 1,035,593.

CLAIM

The ornamental design for a cable guide as shown and described.

DESCRIPTION

FIG. 1 is a perspective view showing of the new design for a cable guide;

FIG. 2 is a top view thereof;

FIG. 3 is a bottom view thereof;

FIG. 4 is a left side view thereof;

FIG. 5 is a right side view thereof;

FIG. 6 is a rear view thereof; and,

FIG. 7 is a front view thereof.

The broken line showing forms no part of the claimed design, and the shading is provided to illustrate contour only and is not an indication of texture, gloss, etc.

1 Claim, 3 Drawing Sheets
